C. E. BRADSHAW.
LIFT CATCH FOR BAGS.
APPLICATION FILED JULY 15, 1918.

1,282,533.

Patented Oct. 22, 1918.

UNITED STATES PATENT OFFICE.

CHARLES E. BRADSHAW, OF WATERBURY, CONNECTICUT, ASSIGNOR TO WORCESTER METAL GOODS COMPANY, OF WATERBURY, CONNECTICUT, A CORPORATION OF MASSACHUSETTS.

LIFT-CATCH FOR BAGS.

1,282,533.

Specification of Letters Patent.

Patented Oct. 22, 1918.

Application filed July 15, 1918. Serial No. 244,869.

To all whom it may concern:

Be it known that I, CHARLES E. BRADSHAW, a citizen of the United States, residing at Waterbury, county of New Haven, 5 State of Connecticut, have invented a certain new and useful Improvement in Lift-Catches for Bags, of which the following is a full, clear, and exact description.

My invention relates to lift catches for 10 bags and has for its object the production of a new and improved lift catch in which the friction is reduced so as to result in improved action.

It further has for its object to provide a 15 lift catch having a spring frame upon which the catch plate is mounted so as to have bearings independent of the catch housing. It further has for its object to provide a lift catch having a spring frame for holding 20 it in either open or closed position, one arm of which acts to support the lifting catch-plate while the other arm performs the holding functions. It further has for its object to provide a lift catch having a lifting catch- 25 plate whose supporting pin does not engage the housing of the lift catch.

The following is a description of an embodiment of my invention, reference being had to the accompanying drawings, in 30 which,

Figure 1 shows a bottom plan view of a lift catch embodying my invention;

Fig. 2 shows a longitudinal sectional view of the same;

Fig. 3 shows a bottom plan view of a 35 modification;

Fig. 4 shows a view in side elevation, with parts broken away to show details of construction;

Fig. 5 is a plan view of the spring forming a part of the spring frame in the safety catches of Figs. 1 to 4;

Fig. 6 is a bottom plan view of a modification of my invention;

Fig. 7 is a side elevation of the same with parts broken away;

Fig. 8 is a detail of the constructions shown in Figs. 6 and 7;

Fig. 9 is a partial bottom plan view showing another modified detail, and

Fig. 10 is a side elevation of the same with parts broken away.

Referring more particularly to the drawings, 1 is a housing having lugs 2-2 for securing it to a bag frame in the ordinary manner. The body portion of this housing

is box-shaped and is provided with upwardly extending struck up portions forming recesses 3-3 for housing certain portions of the spring frame and parts carried thereby, being drawn up in this form from sheet metal. Within the housing is a spring frame composed of a spring 4 shown in detail in Fig. 5 and a tubular bearing member 5 carried by the spring 4, the ends 60 of said spring being bent inward and also bent slightly so that the inwardly bent ends are in substantial alinement with the axes of said recesses 3. The tubular bearing 65 member 5, however, is carried by the spring 4 in such a position that it does not engage any part of the housing, being held free therefrom and being adapted to turn upon the inturned ends of the spring 4 so that the external ends 70 of the tubular bearing are free from all frictional engagement. Inasmuch as the tubular member 5 turns upon the inturned ends of the spring, which ends are of small diameter, the friction due to such turning is slight. The spring 4 is held within the 75 housing 1 by lugs 6-6, which are located on each side of one of the projections 2 and are bent down so as to engage the rear end portions of the spring 4. The lugs 6, being formed from metal adjacent to the lug 2, 80 are formed from metal which would otherwise be waste metal, and therefore do not require metal such as will add to the cost of the catch. 7 is the catch-plate having the catch member 8 riveted thereto at right 85 angles in the ordinary manner. The catch plate 7 is provided at its pivotal end with extensions 9-9, which are bent around the tubular bearing member 5 so as to secure the catch plate member thereto. Between the 90 extensions 9-9 is another extension 10 forming a portion of the hub of the plate and upon which the tongue 11 and the spring 4 bear so as to hold the catch in either open or closed position in the ordinary manner. 95

The spring 4 of the spring-frame is shown in detail in Fig. 5, and while the same can be stamped out of sheet metal, I preferably form it of round steel wire, as shown in Figs. 1 and 2, which is bent into the shape 100 shown, and subsequently hardened and tempered.

In assembling the catch shown in Figs. 1 and 2, after forming the housing 1 by drawing it up from sheet metal and spring-frame 110 composed of the spring 4 and the tubular bearing member 5, I place the spring-frame

within the housing and bend down the lugs 6 so as to hold the same in position. After forming the lift plate 7 with the catch 8 riveted thereto, the extensions 9 being partially bent but so formed that the plate can be applied to the housing in the position shown in Fig. 2, with the extensions 9 projecting upwardly, I apply the plate and then bend the extensions 9 around the tubular member 5, whereupon the formation of the lift catch is completed ready to be attached to the bag frame, the tubular member 5 being carried by the spring 4 with its external end surfaces entirely out of engagement with the housing or any bearing carried thereby, and the spring 4 acting not only to entirely support the tubular bearing 5 and furnish bearings therefor, but having its end 11 in engagement with the holding extension 10 so as to hold the catch plate in either open or closed position.

The construction shown in Figs. 3 and 4 is the same as the construction shown in Figs. 1 and 2, with the exception that instead of employing spring-holding lugs 6—6 adjacent to one of the end lugs, I form lugs 12—12 on the side of the housing which are bent down and engage the outside members of the spring 4. In both cases the lugs are 30 symmetrically disposed and engage symmetrical portions of the frame.

In the construction shown in Fig. 6, the spring-frame 4' is made of sheet metal and the hollow bearing member is formed integral therewith so as to be fixed thereto and held spaced away from the housing. This bearing member is formed by bending up a tang 13 cut out from the body of the spring-frame and bent into semi-cylindrical form as shown in Fig. 7. The end 14 of the spring-frame is also bent into semi-cylindrical form so that the two portions form a round hollow bearing, as shown in Fig. 7, and the lugs 9 of the lift plate are bent 45 around this hollow bearing in the same manner as they are bent around the member 5 of Figs. 1 and 2. The spring frame is held in position by lugs 6' similar to the lugs 6. The spring-frame in Figs. 6 and 7 is shown 50 as formed from a single strip of metal, the portion 11' being bent over on top of the other portion and bearing upon the extension 10 of the catch-plate to hold the plate in either its open or its closed position.

55 The spring-frame, when made of sheet metal, can be made of two portions as shown in Figs. 9 and 10, the two separate parts 4² and 11² being clamped at their right hand ends by lugs 6² as shown. In the form 60 shown in Figs. 6 and 7, the catch-plate turns upon the tubular bearing, the latter being held stationary because integral with the lower portion of the spring-frame. The tubular member in this instance, however, is 65 entirely supported by the spring-frame as

in the construction shown in Figs. 1 and 2, and does not make lateral engagement with any portion of the housing, the spring-frame, together with the bearing for the lift plate, being formed as a complete structure before being mounted in the housing, which feature I believe to be an entirely novel feature in devices of this character and having advantages in manufacture, although, on account of the reduction in friction, I prefer to use the construction shown in Fig. 1, in which the tubular bearing member turns upon the ends of the spring portion of the spring-frame. 70 75

As will be evident to those skilled in the art, other modifications may be made of my invention without departing from the spirit thereof or the scope of the appended claims.

What I claim is:

1. In a lift catch, the combination of a 85 housing, a frame mounted within said housing, a tubular bearing carried by said frame so as to be spaced from said housing, a catch plate having extensions projecting through said housing and surrounding said tubular bearing, and means for securing 90 said frame to said housing.

2. In a lift catch, the combination of a 95 housing, a spring-frame mounted within said housing, a tubular bearing carried by said frame so as to be spaced away from said housing, a catch plate having extensions projecting through said housing and surrounding said tubular bearing, said frame having a centrally located projection 100 engaging the hub portion of said catch plate, and means for securing said frame to said housing.

3. In a lift catch, the combination of a 105 housing having upwardly extending struck up portions forming recesses therein, a spring-frame having inturned ends in line with the axes of said recesses, a tubular bearing carried by said inturned ends and adapted to revolve thereon and free from external friction at its ends, a catch plate having extensions projecting through said housing and surrounding said tubular bearing, and means for securing said spring-frame in said housing. 110 115

4. In a lift catch, the combination of a 120 housing having upwardly extending struck up portions forming recesses therein, a spring-frame having inturned ends in line with the axes of said recesses, a tubular bearing carried by said inturned ends and adapted to revolve therein free from external friction at its ends, a catch plate having extensions projecting through said housing and surrounding said tubular bearing, said 125 spring having a central projection extending beyond said tubular bearing and engaging the hub of said catch plate between said extensions, and means for securing said spring-frame in said housing. 130

5. In a lift catch, the combination of a housing, a frame mounted within said housing, a tubular bearing carried by said frame, a catch plate having extensions projecting through said housing and surrounding said tubular bearing, said spring-frame having a centrally located projection engaging the hub portion of said catch plate, and symmetrically disposed holding lugs integral with said housing and engaging symmetrically disposed portions of said spring-frame so as to hold it in said housing. 10

CHARLES E. BRADSHAW.
